UNITED STATES PATENT OFFICE.

FRANK E. WARNER, OF WATERBURY, CONNECTICUT, ASSIGNOR TO SCOVILL MANUFACTURING COMPANY, OF WATERBURY, CONNECTICUT, A CORPORATION OF CONNECTICUT.

FASTENER-ATTACHING MACHINE.

Application filed April 10, 1924. Serial No. 705,664.

To all whom it may concern:

Be it known that I, FRANK E. WARNER, a citizen of the United States, residing at Waterbury, in the county of New Haven and State of Connecticut, have invented a certain new and useful Improvement in Fastener-Attaching Machines, of which the following is a full, clear, and exact description:

- 10 In the setting or attaching of snap fasteners, such as glove and other similar fasteners, it is desirable that machines for performing the setting operation be as near as possible free of all characteristics which
- 15 have a tendency to impede their operation, either because of failure in the supply of fastener parts to the setting or attaching mechanism of the machine, or because of improper feed of such fastener parts or
- 20 jamming of the fastener parts while being fed, or of failure of the machine to properly position the fastener parts with respect to the setting mechanism, to the end that the operation of the machine may, if desired, be
- 25 continuous and may present no difficulties which entail a loss of time to the operator or which result in improper setting or attaching of the fasteners or complete failure of the setting of a fastener.
- 30 One object of this invention is to provide a machine for attaching snap fasteners or the like, in which proper operation of the feed device for the fastener parts is assured, and which feed device is simple in construction and operation and is not apt to become inoperative due to breakage or other causes.

A further object of the invention is to provide means for actuating the mechanism for feeding fastener parts to setting position which, after having fed a fastener part to such position, will immediately, be partially withdrawn, thus leaving the fastener part free for the application of the material to which it is to be attached or applied and withdrawing from proximity to such fastener part the push finger or pusher which ordinarily, in this type of machine, presents an obstruction to the easy positioning of the material.

A still further object of the invention is to provide, in a machine of this type, means associated with the setting mechanism for receiving and maintaining the fastener parts

in setting position, such means being entirely automatic in their operation and requiring no attention and no adjustment on the part of the operator.

The invention consists in a fastener attaching machine, comprising essentially a setting anvil, above which is positioned a relatively movable setting plunger; and associated with these parts is a raceway adapted to receive fastener parts to be positioned upon the anvil, a chute communicating with the raceway and adapted to supply fastener parts thereto, a movable abutment arranged in the raceway adjacent to the point of supply thereof of the chute and acting as a stop to prevent the entrance into said raceway from said chute of more than one fastener part at a time, a push finger or pusher arranged for longitudinal sliding movement in said raceway and adapted to move fastener parts fed thereto from their point of introduction into the raceway to setting position upon the anvil and acting during this movement as a closure for the end of the chute, and means for imparting the desired movements to the plunger and pusher in timed relation. And the invention consists, further, in a modification of the means for imparting movement to the pusher in timed relation to the movement of the plunger, whereby the pusher will advance a fastener part to setting position upon the anvil and will then be partially withdrawn, and will thereafter be completely withdrawn and returned to position for feeding another fastener part to setting position upon the anvil after the fastener part already positioned thereon has been attached. The invention moreover includes automatic means associated with the anvil for maintaining the fastener part fed thereto in proper position thereon prior to and during the setting or attaching operation, as I will proceed now to explain and finally claim.

In the accompanying drawings illustrating the invention, in the several figures of which like parts are similarly designated, Figure 1 is a side elevation of a machine embodying my invention. Fig. 2 is an enlarged plan view of the anvil, raceway and pusher, the parts being shown in the position assumed by them when a fastener part

has been advanced to setting position upon the anvil. Fig. 3 is a central longitudinal section of the parts shown in Fig. 2, and with these parts in the same positions as in 5 Fig. 2. Fig. 4 is a view similar to Fig. 3, but showing the positions assumed by the parts when the pusher has been retracted for the purpose of advancing a fastener part from its point of introduction into the race- 10 way to setting position upon the anvil. Fig. 5 is a fragmentary side view of a machine similar to that shown in Fig. 1 but including feed hoppers and associated mechanism for supplying fastener parts to the setting 15 mechanism, and embodying the modified form of pusher actuating mechanism hereinbefore referred to, the parts being shown in the positions assumed by them after a fastener part has been moved to setting po- 20 sition upon the anvil, and the pusher has been partially withdrawn. Fig. 6 is a view of parts of the machine shown in Fig. 5, but illustrating the positions assumed by the mechanism when a fastener is being set and 25 the pusher has been withdrawn to a position corresponding to that shown in Fig. 4. Fig. 7 is an enlarged front view of a portion of the machine shown in Figs. 5 and 6, the means for positioning the fastener parts upon the anvil being shown in section and being the same as those shown in Figs. 30 2, 3 and 4. Fig. 8 is a view of parts of the machine as illustrated in Fig. 7, but showing the positions assumed by means for po- 35 sitioning a fastener part upon the anvil when a fastener is being set. Figs. 9 and 10 are, respectively, a top plan view and a central vertical section, greatly enlarged, of 40 a fastener part such as is used with my machine.

The machine comprises a stand 1, carrying a table 2 from which rises a head 3 having a bearing 4 in which is pivoted a lever or rocker arm 5 for operating the plunger 45 6, this plunger being vertically slideable in a bearing 7 carried by the head 3. The lever 5 is actuated through an adjustable link 8 and lever arm 9 by means of a stirrup 10 forming part of an arm 11 longitudinally 50 adjustable in a clarap 12 carried by the lever arm 9. A stop 13 is provided for limiting the upward movement of the plunger 6 by contact with the lever 5.

Mounted upon the table 2 is a bed 14 carrying a pair of complementary guides 15 providing a raceway 16 to which the fastener parts are fed through the chute 17, and arranged to slide in this raceway is a pusher or push finger 18 having gibs 19 55 underlying and cooperating with the guides 15 and by which the pusher 18 is maintained in proper position with respect to the race- 60 way and is held against vertical movement.

This pusher 18 is actuated through a link 20 by means of a lever 21 pivoted at 22 in

a bracket carried by the table 2 and adapted to be oscillated in timed relation to the reciprocation of the plunger 6 by means of a pivotal connection 23 with an adjustable arm 24 swivelled as at 25 to the lever arm 9. 70

Mounted in the bed 14 at its front end and held therein against rotation and against vertical movement by a set screw 26, is an anvil 27 appropriately formed at its upper end to accommodate the particular 75 type of fastener used, and around this anvil and arranged for vertical sliding movement thereon is a sleeve 28 which forms a seat for the flange of a fastener part fed to the anvil. Arranged upon the sleeve 28 for vertical sliding movement with respect thereto and to the anvil is a stop member 29 provided with wings 30 extending to and in contact with the front of the bed 14, and providing a recess at 31 embracing the anvil 80 and the sleeve 28 and forming a pocket into which the fastener parts are fed by the pusher 18 and which properly locates such fastener parts with respect to the anvil and maintains this location of such parts, as 85 will hereinafter appear. The sleeve 28 and stop member 29 are held normally in raised position by springs 32 and 33 respectively, and their vertical movement in both directions is limited by means of slots 34 and 35 90 respectively cooperating with a pin 36 carried by the anvil and extending through these slots (see particularly Figs. 7 and 8).

Located in the raceway, adjacent to the point of introduction of the fasteners there- 100 to from the chute 17, is a detent or stop and brake member 37 provided with a stem 38 arranged for vertical sliding movement within a bore 39 in the bed 14 and held normally in raised position by means of a spring 105 40 surrounding a reduced portion 41 of the stem 38. Upward movement of the member 37 under the influence of spring 40 is limited by a stop screw 42 adapted to contact with the bottom of the bed 14. As will be seen, 110 this stop and brake member normally projects above the bottom of the raceway and it serves two purposes. Its first purpose is to prevent the entrance of more than one fastener part at a time into the raceway when the push finger 18 is withdrawn to the position 115 shown in Fig. 4. Its second purpose is to prevent jumping ahead of the fastener part in the raceway when the push finger 18 moves forward to advance the fastener part 120 to position upon the anvil. This springing or jumping ahead of the fastener part when contacted with by the push finger is due to its springy nature, as will be apparent by reference to Figs. 9 and 10, and sometimes 125 results in such premature advancing of the fastener part from its point of introduction as to permit a second fastener part to be introduced to the raceway from the chute, and 130 to cause jamming of the push finger and

- consequently interruption of the operation of the machine. With the use of the stop and brake member 37, it will be seen that sufficient frictional influence is exerted upon the fastener part to prevent it from jumping ahead, and this frictional influence is maintained until the push finger 18 has contacted with and depressed the stop and brake member.
- 10 For the purpose of facilitating clearing of the raceway, should it become jammed, or obstructed, I articulate one of the guides 15 by pivoting its forward portion 43 at 43' so that it may be swung horizontally upon its pivot to completely open one side of the raceway. This articulated portion 43 of the guide 15 is held normally in alignment with its stationary portion by means of a latch 44 in the form of a circular plate having a portion of its circumference slabbed off as at 45 and provided with a knurled button 46 by which it may be rotated. The portion 43 of the guide is held against upward movement away from the bed 14 by means of a lip 47 cooperating with a complementally formed portion 48 of the bed 14. It will be understood that by turning the latch 44 so that its slabbed-off portion 45 is up, the articulated portion 43 of the guide 15 is free to be swung horizontally upon its pivot 43'.
- The operation of this form of the invention is substantially as follows:—Assuming that the hopper (not shown), which communicates with the chute 17, is filled with fastener parts, this hopper is rotated or actuated in any usual or approved manner to fill the chute with such parts. Now, assuming that the parts of the machine are in the position shown in Figs. 1, 2 and 3, it will be apparent that the fastener parts are prevented from entering the raceway by reason of the fact that the discharge end of the chute 17 is obstructed and closed by the push finger 18. It is first necessary to feed one of the fastener parts in the chute to setting position upon the anvil. This is done by the operator pressing her foot upon the stirrup 10 and through this pressure oscillating the lever arm 9 upon its pivot 9'. This movement will cause the plunger to descend and will at the same time retract the push finger 18 to the position shown in Fig. 4 and will permit access of the fastener parts to the raceway. As hereinbefore pointed out, only one fastener part can enter the raceway because of the stop and brake member 37, which will hold it in the raceway in line with the point of discharge of the chute and will, through it, prevent other fastener parts from descending the chute. The operator then allows the stirrup, and with it the lever arm and other parts, to return to normal position and this return movement will advance the push finger to the position shown in Figs. 1, 2 and 3, and will cause the push finger to advance the fastener part into proper position over the anvil, its proper positioning thereover being ensured by the pocket or recess 31 formed by the stop member 29, the push finger at the same time 70 again obstructing and closing the end of the chute 17. With the parts in this position and the fastener part in proper setting position upon the anvil, the operator then positions the glove or other article to which the fastener is to be applied with the fastener receiving hole preformed in it over the fastener part on the anvil by pressing the article upon the stop member 29 and thus partially depressing this stop member. The 75 operator, with the article so arranged, next places the complemental fastener part over the fastener part on the anvil with the article lying between the two, and holds the article and complemental fastener part in this 80 position while again exerting pressure through the stirrup 10 upon the lever arm 9, thus forcing the plunger down upon the complemental fastener part and by this 85 means depressing the article, and with it the other fastener part and the sleeve 27, so that the appropriately formed upper end of the anvil passes into the fastener part and clinches the complemental fastener part to 90 set the fastener. Obviously, upon this section 95 application of pressure to the stirrup 10 and movement of the lever arm 9, the push finger 19 will be again retracted to the position shown in Fig. 4 and a fastener part 100 will enter the raceway from the chute and be stopped by member 37, and when the setting operation is completed and the pressure upon the stirrup 10 is released, the parts of the machine will again assume the positions shown in Fig. 1, this other fastener part 105 will be moved forward by the push finger to setting position upon the anvil, and the machine will be ready for another setting operation.
- Referring now to the modified form of the machine shown particularly in Figs. 5, 6 and 7, it will be seen that I employ the same stand 1, table 2, head 3, bearing 4, lever 5, plunger 6, bearing 7, link 8, lever arm 9, pivot 9', arm 11 and clamp 12, and also the anvil and raceway and associated parts and all of these parts operate in substantially the same manner as the corresponding parts of the machine just described. In addition to these parts, I mount upon the head 3, bracket 49 supporting a hopper 50. A chute 51 extends from the hopper for the purpose of discharging fastener parts complemental to those carried in the hopper 52 and chute 17, to a pair of jaws 53, carried by and slidably upon the front face of the bearing 7. These jaws 53 are depressed in unison with and by the plunger 6, and are raised by means of a pin 54 carried by the end of the lever 5 and cooperating with fin-

gers 55 carried by the jaws. The jaws 53 are similar in construction and operation to those described in the patent of F. E. Stanley, No. 1,182,594, granted May 9, 1916.

It may be found desirable, especially when the automatic feed provided by the hopper 50, chute 51, and jaws 53 is used, to retract the push finger 18, after it has advanced a fastener part through the raceway to setting position upon the anvil, a sufficient distance from the anvil and the thus positioned fastener part to facilitate application to the fastener part of the article to which it is to be applied, and it is to this end that the modification of the machine, as shown in Figs. 5, 6 and 7, is primarily directed. In detail, the movements of the push finger necessary to accomplish the desired positioning of the fastener part upon the anvil and the retraction of the finger, as above referred to, are as follows:—The push finger must be retracted to the position shown in Figs. 4 and 6, must then move forward to the position shown in Figs. 1, 2 and 3, and must immediately thereafter be retracted to the position shown in Fig. 5. To this end, instead of connecting the lever 56, corresponding to the lever 21, directly to the lever arm 9, I fix this lever 56 upon a shaft 57, and also mount upon this shaft 57 a bell crank lever 58 to the lower end of the arm 58' of which I pivot a link 59 provided with a cam slot 60 with which coacts a roller 61 carried by the lever arm 9. The upper edge of this link is shaped at 62 to provide a cam surface for cooperation with an abutment 63 carried by a bracket 64 mounted upon the table 2. The other arm of the bell crank lever 65 is formed with a cam surface 66 normally engaging a roller 67 carried by the lever arm 9. A spring 68 connected to the lever 56 and to the bed 14 or other part of the machine tends to normally advance the push finger 18 and to exert pressure upon the link 59 for a purpose hereinafter described.

The operation of this modified form of machine is the same, so far as the operation of setting a fastener is concerned, as the operation hereinbefore set forth, except that both of the fastener parts are automatically fed to setting position; but the actuation of the push finger 18 is modified as hereinbefore described in order to facilitate positioning of the article to which the fastener is to be applied, and this modified actuation and the movements of the push finger incident thereto are substantially as follows:—We will assume that the parts of the mechanism are in the positions shown in Fig. 5, that a fastener part has been advanced to the anvil, that the push finger has just been partially retracted, that the article to which the fastener is to be applied has been properly located with respect to the fastener part

upon the anvil, and that a complementary fastener part has been fed to the jaws 53 and pressure is about to be exerted upon the arm 11 to turn the lever arm 9 upon its pivot 9' for setting these two fastener parts and attaching 70 the fastener to the article. When this pressure is applied to the arm 11, and the lever arm 9 is moved in the direction of the arrow, Fig. 5, the roller 61, being in the position shown in the cam slot 60 of the link 59, will force the link 59 forward and will oscillate the shaft 57 and thereby move the lever 56 to retract the push finger. This movement continues with the roller 61 in the same position, due to the slight overhang of the portion 69 of the cam slot 60, until the cam surface 62 contacts and rides upon the abutment 63, at which point in the movement of the link 59, the link will be forced downwardly, and the roller 61 will ride up into the portion 70 of the cam slot 60, and will continue the movement of the shaft 57 and lever 56 and the retraction of the push finger 18, until the completion of the fastener setting operation and the assumption 80 by the parts of the machine of the positions shown in Fig. 6. Now, upon releasing the pressure upon the arm 11, the lever arm 9 will swing back to its normal position as shown in Fig. 5, and in doing so will impart the following movements to the link 59, bell crank lever 58, lever 56 and push finger 18:—Under the influence of the spring 68, the arm 58' will exert sufficient pressure upon the link 59 to cause it to follow the movement of the roller 61 with this roller in the portion 70 of the cam slot 60, and this position of the parts will be maintained to the completion of the forward movement 90 of the push finger 18 to position a fastener part upon the anvil. It is at this moment of the completion of the forward movement of push finger 18 that it is desired to immediately partially retract the push finger, for the purpose above pointed out, and this retraction is accomplished by means of the roller 67 coming in contact with the cam surface 66 of the arm 65 of the bell crank lever 58 causing the bell crank lever to rock the shaft 57, retract the push finger to the position shown in Fig. 5, and cause the link 59 to move forward so that the roller 61 moves out of the portion 70 of the cam slot and comes to rest in the position shown in Fig. 5, where it remains until pressure is again exerted upon the arm 11 to move the lever arm 9, whereupon the same operations will be repeated.

It will be seen that by the provision of the brake and stop member 37, I prevent premature and improper advance of fastener parts to the anvil, and provide a simple sturdy and automatic stop for preventing entrance of fastener parts into the raceway otherwise than successively and sepa- 120

rately, as desired; that I afford, by means of the stop member 29, means whereby the fastener parts are always properly located with respect to the anvil and are prevented from 5 being displaced therefrom during the application of the articles to which they are to be attached; and that, by means of the arrangement of links and levers and their associated cams and rollers, I provide a 10 mechanism for actuating the push finger, whereby ease of operation of the machine is assured and facility of manipulation by the operator of the articles to which the fasteners are to be attached is afforded. In these 15 respects, particularly, my invention embodies advantages, in machines of this character, not heretofore known, so far as I am aware.

Various changes in details of construction 20 and arrangement of parts are contemplated as within the spirit of the invention and the scope of the following claims.

What I claim is:—

1. In a fastener attaching machine, a setting anvil, a setting plunger, a raceway communicating with said anvil, a chute communicating with said raceway and adapted to feed fastener parts thereto, a push finger cooperating with said raceway and adapted 25 to advance to the anvil the fastener parts fed to said raceway, and a stop and brake member arranged in cooperative relation to said raceway and adjacent to the discharge end of said chute, said member adapted to prevent entrance into said raceway from said chute of more than one fastener part at a time and to frictionally engage such fastener parts during their initial movement by said push finger and until said push finger 30 engages said member, to prevent premature movement of said fastener parts in said raceway.
2. In a fastener attaching machine, a setting anvil, a setting plunger, a bed arranged 45 adjacent to said anvil and provided with a raceway, a chute communicating with said raceway and adapted to feed fastener parts thereto, a push finger cooperating with said raceway and adapted to advance to said anvil fastener parts fed to said raceway, and a stop and brake member carried by said bed and normally projecting into said raceway, said member being movable out of normal position by cooperation therewith of 50 said push finger and capable when in normal position of preventing entrance into said raceway from said chute of more than one fastener part at a time and of applying a frictional retarding influence upon such fastener parts when moved by said push finger until said member is moved out of normal position by said push finger, whereby premature movement of said fastener parts is prevented.
3. In a fastener attaching machine, a setting anvil, a setting plunger, a bed arranged 55 adjacent to said anvil and provided with a raceway, a chute communicating with said raceway and adapted to feed fastener parts thereto, a push finger cooperating with said raceway and adapted to advance to said anvil fastener parts fed to said raceway, and a stop and brake member carried by said bed and normally projecting into said raceway, said member being movable out of normal position by cooperation therewith of 60 said push finger and capable when in normal position of preventing entrance into said raceway from said chute of more than one fastener part at a time and of applying a frictional retarding influence upon such fastener parts when moved by said push finger until said member is moved out of normal position by said push finger, whereby premature movement of said fastener parts is prevented.

a cam-link and lever mechanism and means carried by the plunger actuating means and cooperating therewith.

6. In a fastener attaching machine, a setting anvil, a setting plunger, a raceway communicating with said anvil, a chute communicating with said raceway and arranged to supply fastener parts thereto, a push finger slidable in said raceway and adapted 10 to feed the fastener parts supplied to the raceway from their point of introduction thereinto to said anvil, means for actuating said plunger to perform the fastener attaching operation, and means actuated by 15 said plunger actuating means for imparting movement to said push finger, whereby upon the descent of said plunger said push finger will be retracted to a position adjacent to the point of introduction of fastener parts 20 into said raceway and upon the ascent of said plunger will advance a fastener part fed to said raceway into position upon said anvil and then be partially returned toward the point of introduction of the fastener 25 part into the raceway, said means including a cam-link and lever mechanism and rollers carried by the plunger actuating means and cooperating therewith.

7. In a fastener attaching machine, a setting anvil, a setting plunger, a raceway communicating with said anvil, a chute communicating with said raceway and arranged to supply fastener parts thereto, a push finger slidable in said raceway and adapted 30 to feed the fastener parts supplied to the raceway from their point of introduction thereinto to said anvil, means for actuating said plunger to perform the fastener attaching operation, and means actuated by 35 said plunger actuating means for imparting movement to said push finger, whereby upon the descent of said plunger said push finger will be retracted to a position adjacent to the point of introduction of fastener parts 40 into said raceway and upon the ascent of said plunger will advance a fastener part fed to said raceway into position upon said anvil and then be partially returned toward the point of introduction of the fastener 45 part into the raceway, said means including a bell-crank lever carrying on one of its arms a link provided with a cam slot 50

and its other arm formed with a cam surface, rollers carried by said plunger actuating means and cooperating with said cam 55 slot and cam surface, and resilient means for normally advancing said push finger.

8. In a fastener attaching machine, a setting anvil, a setting plunger, a raceway communicating with said anvil, a chute communicating with said raceway and arranged to supply fastener parts thereto, a push finger slidable in said raceway and adapted 60 to feed the fastener parts supplied to the raceway from their point of introduction 65 thereinto to said anvil, means for actuating said plunger to perform the fastener attaching operation, and means actuated by said plunger actuating means for imparting movement to said push finger, whereby 70 upon the descent of said plunger said push finger will be retracted to a position adjacent to the point of introduction of fastener parts into said raceway and upon the ascent of said plunger will advance a fastener 75 part fed to said raceway into position upon said anvil and then be partially returned toward the point of introduction of the fastener part into the raceway, said means including a lever connected with said push 80 finger, a spring arranged to normally pull upon said lever to advance said push finger, a bell-crank rigidly connected with said lever and having a link provided with a cam slot connected to one of its arms and its 85 other arm provided with a cam surface, rollers carried by the plunger actuating means and cooperating with the cam slot and cam surface respectively, a cam surface on said link, and a fixed abutment 90 co-operating with the cam surface of the link, the respective cooperation between the cam slot and its roller and the cam surface of the link and its cooperating abutment serving to retract said push finger, the spring 95 serving to advance the push finger, and the cooperation between the cam surface of the bell-crank arm and its respective roller serving to partially return said push finger, 100 as specified.

In testimony whereof I have hereunto set my hand this 9 day of April, A. D. 1924.

FRANK E. WARNER.
